D. R. FURNAS

DOOR LATCH

Filed Oct. 28, 1925

UNITED STATES PATENT OFFICE.

DON ROSS FURNAS, OF AURORA, ILLINOIS, ASSIGNOR TO AURORA STEEL PRODUCTS COMPANY, OF AURORA, ILLINOIS, A CORPORATION OF ILLINOIS.

DOOR LATCH.

Application filed October 28, 1925. Serial No. 65,344.

This invention relates to improvements in door-latches designed particularly for use in connection with the sheet-metal doors that are employed for metal clothes-lockers and similar structures. It is common to provide such lockers with an inturned longitudinal flange at the free edge of the doorway—that is, the vertical edge portion that is remote from the hinges of the door—and to slidably secure a vertically movable bar to the inner face of the locker frame adjacent to such flange, said bar carrying a plurality of latches rigidly affixed thereto that are adapted to engage with keepers carried by the door. In the act of closing the door the rounded edges of the keepers coming in contact with the latches will force such bar up, and, when the door is wholly closed, the bar will ordinarily move down by gravity so as to effect an interlocking of the latches with their keepers. It sometimes occurs, however, that the bar will not drop, the result being, of course, that the desired latching movement does not take place. It is the object of my invention to provide an improved door latch for lockers, &c., comprising means so located with reference to one of the latches as to automatically break any sticking or binding engagement of the bar and compel its downward movement so as to positively insure the desired latching of the door; also to provide for mounting the locking devices or keepers and the handle or actuating device on the door, and the latch or latches on the locker frame. I accomplish these objects by the construction and arrangement of parts as shown in the drawing and hereinafter particularly described. That which I believe to be new is set forth in the claims.

In the drawings,—

Fig. 1 is a vertical section, partly broken away, through a metal locker and its door, with my improved latching mechanism attached thereto, the section being taken on line *a—a* of Fig. 2;

Fig. 2 is a view showing the inner face of a portion of a locker door and the frame of the doorway therefor, with which the improvements are incorporated, and showing also, in dotted lines, the position of the parts when the latches are raised out of engagement with their keepers. A portion of the doorway frame of a second locker is also

shown and some of the locker walls are shown in vertical section;

Fig. 3 is a horizontal section taken at line *b—b* of Fig. 2;

Fig. 4 is a perspective view of the latch frame; and

Fig. 5 is a detail being a cross-section on line *c—c* of Fig. 1.

Referring to the several figures of the drawings,—5 indicates a portion of the body of a locker formed of sheet metal, as usual, in the open front of which is set a framework to which the walls of the locker are connected as usual, and to one of the vertical side bar members of which the door of the locker will be hinged. This framework in the construction shown comprises two vertical side members 6, each formed of an angle-iron, and upper and lower cross-bars, indicated respectively by 7 and 8, which as here shown are of channel-iron construction. The flanges of the cross-bars and one of the flanges of each side bar extend toward the interior of the locker. The sheet-metal door that fits within this doorway frame and is hinged thereto is indicated by 9, and, as shown, its marginal portions form inwardly-directed flanges, the upper and lower ones of which are indicated respectively by 10 and 11, and, when the door is closed, each lies close to and parallel with a flange of one of the cross-bars. The vertical flange on the free edge of the door is indicated by 12, and, as clearly shown in Figs. 2 and 3, it stands parallel with and at some distance from the inwardly-directed flange of the adjacent side bar member 6 when the door 9 is closed. Riveted to the door flange 12 are a plurality of locking devices or keepers adapted to be separately engaged by latches carried by a latch bar mounted on the locker frame to move vertically, as hereinafter described. The number of keepers and latches may well be varied but as here shown three of such keepers and latches therefor are provided, the keepers being indicated respectively by 13, 14 and 15. As shown each keeper is provided with a deep notch in its upper margin for the reception of a latch, and each has that portion of its upper edge that lies between the notch and its free end sharply inclined downward from such notch.

16 indicates a latch bar lying against the

2
inner face of that one of the vertical side bars 6 that is adjacent to the free edge of the door. Said bar 16 is slidingly secured in place as usual by headed bolts 17 that are affixed to said side bar and extend through slots 17^a in the bar 16. Riveted to the bar 16 are latches 18, 19, and 20 that project laterally across the flange 12 of the door and are adapted to engage respectively with the keepers 13, 14 and 15 that are carried by such flange.

21 indicates a handle for the door, which handle is mounted on the door and has a limited vertical movement with respect thereto by reason of finger portions 22 projecting through short slots 23 in the face of the door. To these finger portions or ends of the handle is bolted a vertically movable latch frame 24 which also serves as a handle supporting member. Said frame as here shown is formed of a piece of sheet metal bent upon itself to U-shape to provide parallel members at opposite sides thereof, the edges of which lie in close proximity to the inner face of the door. Such members are in the form of ears 25, 26 at opposite ends of the member 24 and at one side thereof, and an intermediate elongated ear 27 at the same side, the latter ear being set over to one side of the longitudinal plane of the ears 25, 26, as best shown in Fig. 4. At the opposite side of the member 24 are ears 28, 29 which correspond with the ears 25, 26, respectively. The ears 27, 28 carry rollers 30, 31, respectively, mounted adjacent to the marginal portions of said ears so that they project slightly beyond the edges thereof in position to bear against the inner face of the door. These rollers are preferably mounted in open ended slots 32 in the ears which carry them, as illustrated in Fig. 5, said rollers being provided with annular grooves somewhat wider than the thickness of the ears so that the rollers are held loosely in the slots 32. It will be noted that the rollers 30 and 31 are spaced apart longitudinally of the frame 24 so that the latch frame slides easily along the inner face of the door and does not bind even though the force applied to the handle to move the latch should tend to rock the latch frame about a transverse axis, as would be the case if the handle were gripped near the bottom and pulled up from that point, since as shown in Fig. 1 the end portions of the handle are secured to the ears 25, 26. By the construction described I provide a latch frame that always moves smoothly regardless of where the handle is grasped.

60 Formed with the latch frame 24 are two ears 33 and 34 that are parallel with and adjacent to the inwardly-directed flange 12 of the door, said ears being spaced apart sufficiently to receive between them the latch 19. The lower edge of the ear 33 and the

upper edge of the ear 34 are curved or inclined, as clearly shown in Fig. 1, to permit them to move more easily past the latch 19 when the door is closing, as will be understood. The parts of the mechanism are so arranged relatively to each other that when the door is closed the lower ear 34 will extend alongside of the keeper 14 but with its upper edge sufficiently below the upper edge of such keeper to permit the latch 19 to lie to its full extent in the notch therein, and thus by the interlocking of said latch and its keeper, as well as by the interlocking of the other latches with their keepers, the door will be held in latched position. To release the several latches from their keepers so that the door can be swung open, the handle 21 is raised to the extent permitted by the slots 23, and such movement, through the contact of the ear 34 with the lower edge of the latch 19, will force up the latch bar 16 so as to wholly withdraw the latches from the notches in their respective keepers. The ear 33 is provided as a means for insuring the descent of the bar 16 so as to carry the latches into interlocking engagement with their keepers. By reason of the curved upper edges of the keepers coming in contact with the lower edges of the respective latches, the closing of the door will cause a rising of the latch bar 16, and ordinarily as soon as the latches move over the notches in the keepers the latch bar 16 will drop, thereby seating the latches in such keepers. If however, as sometimes happens, the latch bar 16 should stick in its raised position, then as the door is being closed the curved lower edge of the ear 33 will come in contact with the upper edge of the latch 19, and as such latch rides along said curved edge the bar 16 will be forced down and will carry the various latches against the curved upper edges of their respective keepers, so that during the final closing movement of the door the latches will be brought over and drop into the notches of the keepers. In addition to the parts 18, 19, 20 serving as latches they also serve as stops to limit the inward swinging of the door, for while the latch bar 16 is freely movable up and down it is of course held by the headed bolts 17 against moving away from the member 6 on which it is mounted.

At 35 is shown the casing of a lock that is attached to the inner face of the door. The bolt 36 of the lock is adapted to be actuated by a key inserted in the lock from the front of the door, as usual, and when the bolt is projected, as shown in Fig. 2, it will overlie a shoulder or upper end portion of the vertically-movable latch frame 24 that is connected with the door handle, and thus will effectually lock the door closed, as will be understood. Another locking means is provided that may be used in lieu of or

in addition to the lock 35, such other locking means being a short bar 37 carried by the member 24 and projecting through a hole in the face of the door, through which bar 5 is an opening 38 that registers with an opening 39 through the handle. Through these openings can be passed the shackle of a padlock.

What I claim as my invention and desire 10 to secure by Letters Patent, is—

1. The combination of a locker frame, a vertically movable locking bar supported by one of the side members of said frame, a latch carried by said bar, a door hinged in 15 said frame, a keeper carried by the door, with which keeper said latch is adapted to interlock, and means mounted on the door and operable to positively move said latch into engagement with the keeper.

2. The combination of a locker frame, a vertically movable locking bar supported by one of the side members of said frame, a latch carried by said bar, a door hinged in 20 said frame, a keeper carried by the door, with which keeper said latch is adapted to interlock, and means mounted on the door and movable into engagement with the latch by the closing of the door, said means being 25 operable to move the latch into or out of engagement with the keeper.

3. The combination of a locker frame, a vertically movable locking bar supported by one of the side members of said frame, a latch carried by said bar, a door hinged in 30 said frame, a keeper carried by the door, with which keeper said latch is adapted to interlock from above, and a vertically movable ear carried by the door and located above said keeper, said ear being movable 35 over said latch by the closing of the door, to force it down into engagement with the keeper.

4. The combination of a locker frame, a vertically movable locking bar supported by 40 one of the side members of said frame, a latch carried by said bar, a door hinged in said frame, a keeper carried by the door, with which keeper said latch is adapted to interlock from above, and a vertically movable ear carried by the door and located 45 above said keeper, said ear being movable over said latch by the closing of the door, to force it down into engagement with the keeper, the proximate edges of the keeper 50 and ear being reversely inclined.

5. The combination of a locker frame, a vertically movable locking bar supported by one of the side members of said frame, a latch carried by said bar, a door hinged in 55 said frame, a fixed keeper carried by the door, with which keeper said latch is adapted to interlock, and two vertically movable ears carried by the door and located one above the other, said ears being movable respectively over and under said latch by the

closing of the door, whereby one of said ears will operate to move the latch into engagement with the keeper, and the other ear will operate to move the latch out of engagement with the keeper. 70

6. The combination of a locker frame, a vertically movable locking bar supported by one of the side members of said frame, a latch carried by said bar, a door hinged in 75 said frame, a keeper carried by the door, with which keeper said latch is adapted to interlock, a member carried by the inner face of the door to move vertically, rollers interposed between said member and the door, means on the outer face of the door for moving 80 said member vertically, and means carried by said member for actuating said latch.

7. The combination of a locker frame, a vertically movable locking bar supported by one of the side members of said frame, a 85 latch carried by said bar, a door hinged in said frame, a keeper carried by the door, with which keeper said latch is adapted to interlock, a member carried by the inner face of the door to move vertically, rollers interposed between said member and the door, means on the outer face of the door for moving 90 said member vertically, and means carried by said member for positively moving the latch into engagement with the 95 keeper upon the closing of the door.

8. The combination of a locker frame, a vertically movable locking bar supported by one of the side members of said frame, a latch carried by said bar, a door hinged in 100 said frame, a keeper carried by the door, with which keeper said latch is adapted to interlock, a member carried by the inner face of the door to move vertically, rollers interposed between said member and the door, means on the outer face of the door for moving 105 said member vertically, means carried by said member for positively moving the latch into engagement with the keeper upon the closing of the door, and means carried by said member for moving the latch out of engagement with the keeper. 110

9. The combination of a locker frame, a vertically movable locking bar supported by one of the side members of said frame, a latch carried by said bar, a door hinged in 115 said frame, a keeper carried by the door, with which keeper said latch is adapted to interlock, a member carried by the inner face of the door to move vertically, rollers interposed between said member and the door, said rollers being spaced apart longitudinally of said member, means on the outer face of the door for moving said member vertically, and means carried by said member for actuating the latch. 120

10. The combination of a locker frame, a vertically movable locking bar supported by one of the side members of said frame, a latch carried by said bar, a door hinged 125

4
in said frame, a keeper carried by the door, with which keeper said latch is adapted to interlock, a member carried by the inner face of the door to move vertically, rollers interposed between said member and the door, said rollers being spaced apart longitudinally of said member, means on the outer face of the door for moving said member vertically, and means carried by said member for positively moving the latch into engagement with the keeper upon the closing of the door.

11. The combination of a locker frame, a vertically movable locking bar supported by one of the side members of said frame, a latch carried by said bar, a door hinged in

said frame, a keeper carried by the door, with which keeper said latch is adapted to interlock, a U-shaped frame carried by the inner face of the door to move vertically, 20 rollers interposed between the opposite margins of said frame and the inner face of the door, said rollers being spaced apart longitudinally of said frame, means on the outer face of the door for moving said member vertically, means carried by said member for positively moving the latch into engagement with the keeper upon the closing of the door, and means carried by said member for moving the latch out of engagement 25 with the keeper.

DON ROSS FURNAS.
